UNITED STATES PATENT OFFICE.

MARY SWEENEY, OF ALLEGHENY, PENNSYLVANIA.

DESIGN FOR A SAD-IRON.

SPECIFICATION forming part of Design No. 26,301, dated November 17, 1896.

Application filed October 9, 1896. Serial No. 608,421. Term of patent 14 years.

To all whom it may concern:

Be it known that I, MARY SWEENEY, a resident of Allegheny, in the county of Allegheny and State of Pennsylvania, have invented a new and original Design for Irons; and I do hereby declare the following to be a full, clear, and exact description thereof.

Figure 1 is a perspective view of my design. Fig. 2 is a cross-section.

The body of the iron *a* has the rounded contour *b*, with the flat portion *c* forming the bottom of the same. The forward end of the body portion has the nose *d*, formed by the inclined face *e* and the inwardly-tapering sides *f*. The heel *g* of the iron is formed by the sloping end face *h*. The handle is represented by the letter *i*. The shape of the body portion with the rounded contour and flat bottom furnishes a shape which is pecul-

iarly adapted to polishing shirt fronts, as by 20 grasping the iron by the handle and dipping it from side to side, so that the rounded portions *b* will be brought into contact with the linen, this polishing operation can be performed quickly and with great effect. The 25 peculiar shape of the nose *d* has the advantage of permitting the iron to enter the ruffles and other contracted openings which it is impossible to reach with an ordinary iron.

What I claim is—

The design for irons, substantially as shown. In testimony whereof I, the said MARY SWEENEY, have hereunto set my hand.

MARY SWEENEY.
